Inventor:

Charles D. Hazen
By Franklin N. Hough

UNITED STATES PATENT OFFICE.

CHARLES D. HAZEN, OF MARTINSBURG, NEW YORK.

DEVICE FOR BENDING WOOD.

SPECIFICATION forming part of Letters Patent No. 367,977, dated August 9, 1887.

Application filed March 30, 1887. Serial No. 233,033. (No model.)

To all whom it may concern:

Be it known that I, CHARLES D. HAZEN, a citizen of the United States, residing at Martinsburg, in the county of Lewis and State of New York, have invented certain new and useful Improvements in Devices for Bending Wood; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 This invention relates to certain new and useful improvements in devices for bending wood, and the apparatus herein described is more especially adapted for forming plow-handles.

20 The novelty of the invention consists in the peculiar combinations, and the construction, arrangement, and adaptation of parts, all as more fully hereinafter described, and then specifically defined in the claims.

25 The invention is clearly illustrated in the accompanying drawings, in which—

Figure 1 is a perspective view of my improved device, representing a plow-handle bent therein. Fig. 2 is a top plan of the same with parts removed and others represented by dotted lines. Fig. 3 is a side elevation, partly in section. Figs. 4, 5, and 6 are details, which will be fully hereinafter referred to.

35 Referring to the details of the drawings, A represents the bed-plank, provided near one end with the bifurcated block a, either formed integral with or rigidly secured to said bed-plank. Near its longitudinal center this bed-plank is provided with a transverse recess or groove, a', and in this recess is a longitudinal slot, a''. In line with this slot is the depression B, which permits the operator to readily lift the bar D' out of the recess D, in line with 40 which, near the other end of the bed-plank, is the depression b, though the first-named depression may be omitted. Secured to the bed-plank intermediate of these depressions are the guide-strips B', so placed that the space 45 between them will be in line with the said depressions. Between the block a and the recess a' the bed-plank is provided with a plu-

rality of holes, C C², preferably four in number, the object of which will be hereinafter stated. Between said block and recess said 55 bed-plank is also provided, upon opposite sides of a line drawn through its longitudinal center, with holes C', preferably two in number, and also with an inclined slot, c', the object of which will be hereinafter set forth. Within 60 a recess, D, at a point just beyond the transverse groove a', I pivot the bars D', the free ends of which are slotted, as shown at d.

E E are bars or strips placed across the recess a' in such a manner as to leave a space, e, 65 between them and a space beneath them, between said bars and the lower wall of the recess a'.

F is a removable block of substantially the form shown, and provided with pins f, which 70 pass entirely through the same and project upon opposite sides thereof, which pins are designed to engage either the holes C or C', as the case may be, the position of said block being changed as it is desired to form either a 75 right or left hand handle. This block is so formed that both sides are used for the shaping of either right or left hand handles—that is to say, when in position shown in full lines it shapes one form of handle, and when reversed, as shown in dotted lines, it shapes the other form of handle. This block is provided at one end with bifurcations f', designed to engage a projection of the block a, as shown in Fig. 2. G G are removable pins designed to 80 engage the holes C² at times during the process of bending.

H is a pin or post provided with a shank somewhat smaller than the slot c' and adapted to engage therewith, said shank being made 90 smaller than the slot, so as to allow the post to be adjusted therein when desired.

I is a locking pin or key, made wedge-shaped, and preferably with offsets or shoulders i to engage the links D' and prevent endwise displacement of said locking-pin, which pin or key is adapted to engage the slots of the bars D', for a purpose soon to be described.

J is a spring-strip or bender, provided at one end with a hook, j, which end is designed 100 to fit into the space e between the strips E. When the wedge K is inserted into the groove a' beneath the strips E, it engages said hooked end and firmly locks the same in place. The

opposite end of this bender is formed with a hook, L, with which engages the clevis M, pivoted to the grapple stay-brace or bender N, which is provided with a shoulder, N', and a hooked end, n, and a shoulder, n'. The shoulder N' of the stay-brace serves to form a secure bearing for the end of the bending-lever.

O is the bending-lever, curved as shown, to correspond with the curvature of the grapple stay-brace, and provided with a shoulder, o, which in practice is designed to engage the shoulder N' and form a purchase therefor.

The operation of the device is as follows: It being our purpose to first form a mold-board or right-hand handle, the removable block F is placed in the position indicated in Fig. 1 of the drawings. The spring bending-strip J is then placed in position, with the hook j fitted into the space e. The heel of the handle to be bent is then placed in position within the recess in the block a, and the handle is then pressed against the block F until the fulcrum-post H can be set in the hole C', which is provided at a point necessary to secure the desired bend or curve to the handle. By thus regulating the position of the post any desired curve may be secured. The handle is then pressed back against the post until the pin f can be set in the hole C nearest to the slot c. The key or wedge K is then pressed within the groove a' a sufficient distance to cause the heel of the handle to bear well against the block a. The clevis M of the bender N is then applied to the plate-hook L, and the operating-lever O is applied in such a manner as to cause the shoulder o of the lever to bear against the corresponding shoulder n' of the stay-brace. The lever is then forced downward until the desired bend is obtained, when the locking-pin I is forced into place within the slots of the bars D'. The lever O may then be removed, and the bent handle, thus locked in position, is in readiness for kiln-drying. In bending a left-hand handle the block F is placed upon the opposite side of the bed-plank, its ends are reversed, and the block is turned over, the pins f, which project from opposite sides of the block, fitting in the holes C'. The block when thus placed will occupy the position indicated by dotted lines in the drawings. The process just described for bending a right-hand handle is then repeated, excepting that the post H is omitted and the handle is pressed against the block F until both of the stay-pins can be inserted. It will be observed that in bending a left-hand handle the post H is dispensed with and the pins G are inserted in the holes C' and serve to hold the handle in position against the block F.

Having thus fully described my invention and set forth its merits, what I claim to be new, and desire to secure by Letters Patent, is—

1. The combination, with the bed-plank

provided with holes C C', of the removable and reversible block F, provided with pins f, 65 projecting from opposite sides of the block and adapted to the holes C C', substantially as and for the purpose described.

2. The combination, with the bed-plank provided with block a, having bifurcated end, 70 and with holes C C' and inclined slot c', of the block F, pins projecting from each side of said block F, and post H, substantially as and for the purpose described.

3. The combination, with the bed-plank 75 having block a, holes C C', the inclined slot c', and holes C', of the removable reversible block F, provided with pins f, as shown, the removable post H, having a shank engaging said slot, and the removable pin G, substantially as and for the purpose described.

4. The combination, with the bed-plank provided with block a and holes C, C', and C', 80 of the reversible removable block F, provided with pins f, and the removable pins G, substantially as and for the purpose described.

5. In a device for the purpose described, a spring bending-strip provided at opposite ends with hooks, as j L, combined with a clevis engaging said hook L, and a stay-brace carrying said clevis, substantially as and for the purpose described.

6. The combination, with the bending-strip provided with hook L, of the grapple stay-brace, and clevis M, pivoted to said stay-brace, 95 and a removable lever engaging said stay-brace, substantially as and for the purpose described.

7. The combination, with the bed-plank recessed transversely, as at D, as described, of 100 the bars D', pivoted to said recess, and slotted, as described, the bending-strip J, having hook L, the grapple stay-brace N, provided with hooked end n and clevis M, and the key I, substantially as and for the purpose described.

8. The combination, with the bending-strip J, provided with hook L, of the grapple stay-brace N, formed with shoulders N' and n', the clevis M, pivoted to said stay-brace, and the lever O, having curved end and provided with 110 shoulder o, substantially as and for the purpose described.

9. The combination, with the bed-plank, of the bars D', pivoted to said bed-plank and slotted, as described, the bending-strip J, 115 grapple stay-brace N, the clevis carried by said stay-brace and engaging said strip, and the removable key I, all substantially as and for the purpose described.

In testimony whereof I affix my signature in 120 presence of two witnesses.

CHARLES D. HAZEN.
